J. E. FIFIELD,
CORE FOR MOLDING HOLLOW WALLS,
APPLICATION FILED JUNE 12, 1920.

1,373,877.

Patented Apr. 5, 1921.

JASPER E. FIFIELD.
INVENTOR.
BY A.B. BOWMAN
ATTORNEY

UNITED STATES PATENT OFFICE.

JASPER E. FIFIELD, OF SAN DIEGO, CALIFORNIA.

CORE FOR MOLDING HOLLOW WALLS.

1373.877.

Specification of Letters Patent. Patented Apr. 5, 1921.

Application filed June 12, 1920. Serial No. 388,613.

To all whom it may concern:

Be it known that I, JASPER E. FIFIELD, a citizen of the United States, residing at San Diego, in the county of San Diego and State 5 of California, have invented certain new and useful Cores for Molding Hollow Walls, of which the following is a specification.

which the following is a specification of my invention.

My invention relates to molds for forming voids in concrete walls for building construction and the objects of my invention are: first, to provide a mold which has a smooth outer surface and is collapsible so that it may be collapsed and removed after the concrete has partially set; second, to provide a mold of this class in which voids of rectangular shape may be readily molded; third, to provide a mold of this class in which the side plates are interchangeable and may be used for different width voids, the only requirement being the substitution of different end members for creating different width voids in the walls of concrete buildings during construction; fourth, to provide a structure of this class in which the separate engaging portions are on an angle so that with slight raising of the end member they readily separate and collapse and fifth, to provide a mold of this class which is very simple and economical of construction, durable, easy to operate, easy to install and remove and which will not readily deteriorate or get out of order.

With these and other objects in view as
will appear hereinafter my invention con-
sists of certain novel features of construc-
tion, combination and arrangement of parts
and portions as will be hereinafter de-
scribed in detail and particularly set forth
in the appended claims reference being had
to the accompanying drawings and to the
characters of reference thereon which form
a part of this application in which:

Figure 1 is a top view of two of my mold structures shown mounted in position in the wall and showing the wall fragmentarily; Fig. 2 is a fragmentary side elevational view of one of the molds shown positioned in the wall; Fig. 3 is an end view thereof; Fig. 4 is a fragmentary sectional view through 4-4 of Fig. 1; Fig. 5 is a sectional view on an enlarged scale through 5-5 of Fig. 2; Fig. 6 is a sectional view on an enlarged scale through 6-6 of Fig. 3 and Fig. 7 is a perspective view of the mold with narrower end plates for making narrower voids.

Similar characters of reference refer to similar parts and portions throughout the several views of the drawings.

The side plates 1, end plates 2 and separator bars 3 constitute the principal parts and portions of my wall void mold. The side plates 1 are the same shape and are therefore interchangeable. They are each provided at one side with a downwardly tapered edge and with a conforming tapering strip 1^a on one side separated by a separator 1^b and the three riveted together forming a tapering groove along the one side edge of the member 1. The opposite side is provided with a right angled bend 1^c and with a tapering edge on said right angled bend and spaced apart therefrom is a conforming strip 1^d provided with a divider 1^e for separating the portion 1^c from the member 1^d and leaving a like tapering slot. The end plates are also of the same shape and therefore interchangeable and are provided with offset tapering sides 2^a along one edge and with a right angled bend 2^b along the other edge and on the edge of the portion 2^b is provided an offset angled portion 2^c conforming to the angle of the members 1, 1^a and 1^b so that when these offset portions are mounted in the slots the outer surfaces of the members 1 and 2 are flush thus providing a smooth outer surface for the mold structure and when the end members 2 are positioned as shown in the drawings in their relative position with the members 1 there is provided a hollow box shaped form which may be positioned in the wall and the cement poured around the same and after it has set sufficiently to become firm the members 2 may be raised by the application of a bar in connection with the lugs 2^d on the inner surface of the end members 2.

Secured to the side members 1 intermediate their ends are bifurcated lugs 3^a in which are pivotally mounted the ends of the spreader bar 3 preferably by means of 100 tapering pins 3^b conforming to holes in the lugs adapted for said pins for connecting the ends of the spreader bar 3 with the lugs 3^a. It will be noted that these spreader bars 3 are positioned on an angle to permit the 105 side members 1 to move toward each other when the end members are removed and that the side plates 1 are interchangeable and may be used for different width voids; the end plates 2 however are of different widths 110

to provide for varying width voids and are used interchangeably end for end and in connection with the side members.

Though I have shown and described a particular construction, combination and arrangement of parts and portions I do not wish to be limited to this particular construction, combination and arrangement but desire to include in the purview of my invention the construction, combination and arrangement substantially as set forth in the appended claims.

It is obvious that with this construction there is provided a mold for making voids in concrete walls so constructed that the void may be substantially rectangular in form; that the end members 2 when positioned form a rigid support in connection with the side members for providing voids in concrete wall structures; that said end members being tapered may be readily released by upward pressure against the lugs 2^a and as soon as moved slightly may be readily drawn and the spreader bars 3 being pivoted on the tapered pins 3^b in the lugs 3^a the sides will collapse thus providing for the ready removal of the mold whereby it may be repositioned in another place and used again for the same purpose; that in case it is desired to make narrower voids of the same length the same side members can be used and similar end members of narrower width provided with the same angles and operated in the same way. In this case, however, the spreader bars 3 must be shorter.

Having thus described my invention what I claim as new and desire to secure by Letters Patent is:

1. A mold for forming voids in concrete walls, including side plates provided with an inclined edge at one side and with a right angled turn at the other side provided with an inclined edge and end members each provided with a right angled turn, with conforming angles on its side edges adapted to engage the angles on said side members.

2. A mold for forming voids in concrete walls, including side plates provided with an inclined edge at one side and with a right angled turn at the other side provided with an inclined edge, end members each provided with a right angled turn, with conforming angles on its side edges adapted to engage the angles on said side members and means for supporting said side members relatively to said end members whereby the outer surfaces of said members are in a straight line.

3. A mold for forming voids in concrete walls, including side plates provided with an inclined edge at one side and with a right angled turn at the other side provided with a similarly inclined edge, end members each provided with a right angled turn and with conforming inclined edges adapted to engage the inclined edges on said side mem-

bers, means for supporting said side members relatively to said end members whereby the outer surface of said members are in a straight line and spreader bars pivotally connected at each of its ends to lugs on said side members provided with tapering pins whereby they may be readily released and either end of said spreader bar collapsed against said side member.

4. A mold for forming voids in concrete walls, including a pair of interchangeable side members, each provided with a slotted inclined edge and its opposite side turned at a right angle and provided with a slotted inclined edge and a pair of interchangeable end members, each provided with a right angled turn and its edges provided with offset portions adapted to engage the slots in said side members whereby said members are flush with each other at the joints on their outer surface.

5. A mold for forming voids in concrete walls, including a pair of interchangeable side members, each provided with a slotted inclined edge and its opposite side turned at a right angle and provided with a slotted inclined edge, a pair of interchangeable end members, each provided with a right angled turn and its side edges provided with offset portions adapted to engage the slots in said side members whereby said members are flush with each other at the joints on their outer surface and lug means secured to said end members to facilitate the upward movement of said end members relatively to the side members whereby they are released from said side members after a slight upward movement.

6. A mold for forming voids in concrete walls, including a pair of interchangeable side members, each provided with a slotted inclined edge and its opposite side turned at a right angle and provided with a slotted inclined edge, a pair of interchangeable end members, each provided with a right angled turn and its side edges provided with offset portions adapted to engage the slots in said side members whereby said members are flush with each other at the joints on their outer surface, means secured to said end members to facilitate the movement of said end members relatively to the side members whereby they are released from said side members after a slight upward movement and means for supporting said side members relatively to each other intermediate their ends consisting of a bar releasably connected at its opposite ends to said side members.

7. A device of the class described, including four plates, each provided with a right angled turn, two of said members provided with downwardly, enlarging, inclined edges and the other two members with upwardly, enlarging, inclined edges conforming to the edges on the first two mentioned plates.

8. A device of the class described, including four plates, each provided with a right angled turn, two of said members provided with downwardly, enlarging, inclined edges and the other two members with upwardly, enlarging, inclined edges conforming to the edge on the first two mentioned plates and

spreader bars pivotally connecting said side members positioned at an angle therebetween.

In testimony whereof, I have hereunto set my hand at San Diego, California this 5th day of June 1920.

JASPER E. FIFIELD.
